AIR SEAL

Filed Feb. 18, 1929

Inventor
S. Vermilye

By his Attorney *B. Joffe*

UNITED STATES PATENT OFFICE

SHERWOOD VERMILYE, OF LOUISVILLE, KENTUCKY, ASSIGNOR TO LOUISVILLE DRYING MACHINERY CO., INC., OF JEFFERSON COUNTY, KENTUCKY

AIR SEAL

Application filed February 18, 1929. Serial No. 340,849.

My invention relates to air seals for dryers of the direct heating type and has reference more particularly to means for preventing air in-leakage at points where clearance has to be provided between the stationary and the movable parts of the dryer.

This invention is characterized by the provision of a flexible fabric membrane impermeable to air, surrounding the clearance and carrying thereon a movable member which is adapted to be drawn against the seat provided therefor on the movable part, by the drag caused on the member which is attached to the membrane by twisting the fabric of the membrane.

In the appended drawing forming part of this application, Figure 1 is a cross section through a dryer portion provided with an air seal embodying my invention, this section being taken on line 1—1, Figure 2.

Figure 2 is a cross section on line 2—2, Figure 1.

The stationary part 5 of a dryer has a clearance 6 around the movable part 7, so that the latter could rotate without interference from the stationary part 5. The movable part 7 is provided with an annular member or ring 8; as shown, it is a U-channel which is either welded or otherwise firmly secured to the movable part 7 to revolve therewith. Within the channelled annular member 8, a sealing ring 9 is mounted, which is of a slightly larger diameter and smaller width, so as to provide for expansion both diametrically and laterally of the ring and the movable and stationary parts of the dryer.

To the ring 9 is secured one end of a sleeve 10 made of a flexible fabric of sufficient heat resistance and impermeable to air. The other end of said sleeve 10 is secured to the stationary part 5 of the dryer about the clearance 6.

As the part 7 of the dryer rotates, the annular member 8 revolves therewith, causing a drag on ring 9, which twists slightly the fab-

ric of the sleeve 10, thus drawing the face 11 of the ring 9 against the face 12 of the flange of the annular member 8, the faces 11 and 12 forming the seal. This drag is maintained as long as the part 7 revolves, thereby maintaining the ring 9 seated against the annular member 8, and thereby preventing air from passing into the dryer through the clearance 6.

Suitable means for lubricating the contacting surfaces of the ring are provided but not shown in the drawing.

In place of a U-channel ring, a ring of an angle iron may be used, the side of the angle iron forming the flange serving as a seat for the ring attached to the flexible fabric.

I claim—

1. An air seal for a clearance between a stationary and a rotatable part, comprising an annular member on the rotatable part, a ring on the annular member free to move thereon laterally and circumferentially, said ring and annular member having sealing faces, and an air impermeable fabric sleeve about the clearance secured at one end to the ring and at the other end to the stationary part, said sleeve fabric being adapted to twist to draw the ring to bring its sealing face against that of the annular member.

2. In an air seal for a clearance between a stationary and a revolvable part, an annular member secured to the revolvable part and having a flange, a ring mounted on the annular member, so that the same can freely revolve therein, and said ring being free to move laterally to and from the flange, and an air impermeable fabric sleeve about the clearance secured at one end to the stationary part and at the other end to the ring, said sleeve fabric being free to twist under the drag caused by the frictional engagement of the two rings.

3. An air seal for a clearance between a stationary and a movable part, comprising a pair of annular members with faces to form a

10 seal, said members being movable relatively, axially and rotatably, an impermeable fabric sleeve about the clearance connected at one end to the stationary part and at the other end, to one of the annular members, said sleeve being free to twist and draw the annular member connected thereto laterally to bring its sealing faces toward the other annular member when said movable member rotates.

SHERWOOD VERMILYE.
